UNITED STATES PATENT OFFICE

2,366,576

ANIMATED FIGURE

Frank E. Thomas, Chicago, Ill.

Application March 11, 1942, Serial No. 434,228

8 Claims. (Cl. 46—150)

This invention relates to animated figures particularly quadrupeds whereby the principal object is to provide animation or motion by virtue of the mechanism of two legs of the animal, in this particular case the front two legs have been indicated in the drawings as being the motivating elements in this invention.

Another object of my invention is to provide a unique cam actuating means which will furnish locomotion to the forward legs of an animal thereby causing the rearward legs to be advanced and in a manner whereby the advancement of the animal is made in a cycle of time corresponding to a slow advance movement compared to a quick and rapid return movement of the said legs during the idle period to repeat the cycle once again.

Other objects, features and advantages resident in my invention will become apparent from an examination of the accompanying drawings and the ensuing description wherein like numerals are used to designate like parts and in which;

Fig. 1 is a front elevational view showing my invention and the relative movement thereof after a cycle has been completed.

Fig. 2 is a fragmentary and enlarged cross-sectional view of the body of an animal having incorporated therein the mechanism necessary for animation and locomotion.

Fig. 3 is an obliquely transversal cross-sectional view on the line 3—3 of Figure 2.

Fig. 4, Fig. 5, Fig. 6, and Fig. 7, show the motion of the foreleg elements at various stages of a single cycle of cam operation.

Referring, more particularly, to the drawings Figures 1, 2, and 3, my invention, generally, designated 8 showing a giraffe-like animal having integral with the body thereof the rearward legs 9 to which are secured ball-bearing supports 10 to minimize friction when the same are slid along the surface of support 10'. The body is, preferably, hollow in construction as indicated at 11, in order to provide facilities for assembling therein the necessary mechanism needed for animation.

The mechanism comprises motive power means such as a spiral spring 12 secured at the point 43, and further secured to the motivating or driver shaft 14 housed in suitable journals or bearings 15. The shaft 14 is provided with a square portion 44 to which a key may be applied for winding the spring and storing the potential energy therein which would furnish the motivating power for the mechanism enclosed in the shell comprising the body of the animal.

To the shaft 14, is secured a pulley member 13 which drives a pulley member 17 by virtue of the belt connection 16, which is, preferably, of a V belt type in order to assure good frictional contact for efficient transmission of power. The pulley 17 is secured to the shaft 21 journaled in the lugs or bearings 20 and to which is also secured, preferably, at its central position, the pinion designated 18. The said pinion meshes with the larger annular or ring gear designated 19, and which is secured by frictional or "press" fit to the cam structure designated 45. The said cam is provided with suitable grooves 24 in order to allow the lugs 23 to locate and confine the said cam rotatably.

The offset portion 22, is provided in order to relieve friction and provide a most efficient means of mounting the cam structure 45. The cam structure 45 is provided with a cam raceway 25, which is of such curvature as to effect a slow arcuate movement of the legs 31 to the left looking at the drawing Figure 2, causing the legs 9 to advance slidably to the position indicated in dotted lines in that view. The legs are preferably made up of elements 31 and 26 which are rigidly secured to the shaft 30 operating in suitable bearings located on the body of the animal and designated 46. The shaft rocks in the said bearing portions 46 causing the levers 26 and 31 to operate integrally and simulate bellcrank action. The leg structure is preferably made of the element 26 integrally secured to the element 31 as heretofore explained, articulately secured to the lower element 33 simulating the knee action of the leg of an animal, by providing the chamfered portion 32 to permit the legs to bend inwardly and arcuately, whereas causing them to be firm to resist bending when moved in the opposite direction.

The reason for this structure will be readily understood as the description ensues and further elucidates the operation of my invention. The element 33 is articulately secured to the element 31 at the point 34 and at this pivot point a flat spring having one or more coils secured about the pivot 34, being further anchored by anchorage pins 35, will, normally, tend to hold the elements 31 and 33 in the position shown in full lines in Figure 2. Any tendency to bend the legs at the knee at 34 would be, normally, returned to the full lines position indicated by virtue of the actuation of the spring element 36.

The roller that is connected slidably to the slotted portion 21 of the lever 26 is, preferably, made of a button element 28 having a shank extension 43 on which the roller 29 rotatably

operates, the roller being the same size to fit the cam race 25. By virtue of the slotted portion 27, the effective movement during the cycle of operation, that is, namely, advancing the figure forward is done in a certain predetermined length of time, and by virtue of the slotted portion 27, the roller changes the ratio between the lever 26 and the assemblage of the levers 31 and 33, thus providing a quick return movement during the idle period when the toy is not being advanced. This will give an action of locomotion simulating very closely that of the actual animal the giraffe, causing an intermittent hopping action.

The front legs are, preferably, tipped with frictional pads or shoes 37 which may be made of rubber or any other suitable material. In Figures 4, 5, 6, and 7, the operation of the cam is more clearly elucidated. In Figure 4, the rotation of the cam being in the direction indicated, will cause the roller to advance to the high point of the cam 39 in which event the leg will move to the left as indicated by the arcuate arrow indicating the movement.

Inasmuch as the leg is made of a length which when swinging in the arcuate direction shown, tends to lift the animal, it will do so and perform the operation causing the weight of the fore-part of the animal to be shifted from the static support 47 to the motivating leg members generally designed 31 and 33, thus permitting the movement of the legs in the said arcuate direction to cause the rearward leg portions to slide forward to the dotted position shown in Figs. 1 and 2. The static support 47 is, preferably, provided with a ball-bearing member 48 in order that it may give the device or the toy when in static posture a tripod type of support comprised of the two rearward legs and the front static support 47 which is the ideal construction according to the engineering principles for supports.

The four legs are operated in unison or synchronism, being motivated by the cam races 25 on opposite sides of the cam structure 45, the said races 25 being congruent or coincident with respect to their position on opposed faces of element 45.

In Figure 4, the cam race 25 is advancing toward the peak of the cam 39 thus performing the movement of the legs in the direction of the arrow indicated. In Figure 5, the cam race is approaching the still higher point 40 throwing the legs backward and permitting the animal once again to rest on its forward static support 47. Inasmuch as, the locomotion part of the cycle has been completed, and the leg is about ready to return to its original position, Figure 6, and Figure 7, elucidate the idle movement of the said cycle.

Figure 6 shows the point 41 about to be contacted by the roller when the legs will be caused to move in the direction to the right indicated by the arcuate arrow shown, and since the leg is longer than the distance provided when the static forward support is supporting the toy, it may be essential that the element 33 of the legs be caused to bend as at the knee 34 indicated in Figure 7. Then the roller working within the cam is about to reach the point 42, and ultimately the lowest point 38, whence the cycle is to be repeated dependent on the continual rotation of the cam structure in accordance with the arrows indicated thereon.

I believe I have described, succinctly, the nature and operation of my invention, and it is

understood that I hereby reserve any and all improvements coming within the scope and spirit of my invention and the purview of the accompanying drawings.

Having thus revealed my invention, what I claim as new and desire to secure by Letters Patents is:

1. In an animated figure, motivating means adapted to produce locomotion of the said figure by virtue of motivation of the fore-members of the said figure, the rear support members of the said figure being integral with the body thereof, and static support means rigidly connected to the body of the said figure adjacent the said fore-members.

2. In an animated figure, motivating means adapted to produce locomotion of the fore-members of the said figure, the locomotion of the said fore-members producing a resultant complementary locomotion of the rear portion of the said figure, the rear support members of the said figure being integral with the body thereof, and static support means rigidly connected to the body of the said figure adjacent the said fore-members.

3. In an animated figure, cam motivating means adapted to produce locomotion of the said figure by virtue of motivation of the fore-members of the said figure, rear support members of the said figure being integral with the body thereof, and static support means rigidly connected to the body of the said figure adjacent the said fore-members.

4. In an animated figure, cam motivating means adapted to produce locomotion of the fore-members of the said figure, the locomotion of the said fore-members producing a resultant complementary locomotion of the rear portion of the said figure, the rear support members of the said figure being integral with the body thereof, and static support means rigidly connected to the body of the said figure adjacent the said fore-members.

5. In an animated figure, cam motivating means adapted to produce locomotion of the fore-members of the said figure, the said cam motivating means provided with raceway means adapted to produce slow advance movement as compared to a rapid return or idling movement of the said fore-members, and static support means rigidly connected to the body of the said figure adjacent the said fore-members and adapted to support the said figure in an advanced position during the said idling of the cycle of motion of the said fore-members.

6. In an animated figure, cam motivating means adapted to produce locomotion of the fore-members of the said figure, the rear support members of the said figure being integral with the body thereof, the locomotion of the said fore-members producing a resultant complementary locomotion of the rear portion of the said figure, the said cam motivating means provided with dual raceway means adapted to produce deliberate advance movement of both said fore-members simultaneously as compared to a rapid return or idling movement of the said fore-members for each cycle of operation, and static support means rigidly connected to the body of the said figure adjacent the said fore-members and adapted to support the said figure in an advanced position during the said idling of the cycle of motion of the said fore-members.

7. An animated figure comprising, a hollow body having a head portion and rear leg por-

tions integral therewith, motivating means secured within the said hollow body, cam means rotatably secured within the said hollow body, transmission means coupling the said motivating means with the said cam means, fore-leg means articulately secured to the said hollow body means, and connected by virtue of roller means to the said cam means, the said fore-leg means adapted to pendulate arcuately advancing the said figure when the said fore-leg means is motivated in one direction, and idling on the return stroke completing the cycle, and static support means rigidly connected to the body of

the said figure adjacent the said fore-leg means, and adapted to support the said figure in an advanced position during the said idling period of the cycle of motion of the said fore-leg means.

- 5 8. In an animated figure, motivating means adapted to produce locomotion of the fore-members of the said figure, the rear support members of the said figure being integral with the body thereof, and static support means secured to said figure forwardly of said fore-members adapted to support said figure during the idling period of said fore-members.

FRANK E. THOMAS.
